UNITED STATES PATENT OFFICE

AMBROZ DEMEK, OF GRANGER, TEXAS

NUTCRACKER

Application filed June 15, 1928. Serial No. 285,696.

This invention relates to nut cracking machines, and embodies amongst other features, means for singly conveying the nuts from a hopper to a tray from which they are cracked, and subsequently dropped from the tray into a suitable receptacle, the mechanism being very simple and also very efficient in operation for the purposes intended, and which mechanism is actuated 10 or controlled incident to the turning of a hand wheel.

The nature and advantages of the invention will be better understood when the following detailed description is read in connection with the accompanying drawings, 15 the invention residing in the construction, combination, and arrangement of parts as claimed.

In the drawing forming part of this application, like numerals of reference indicate similar parts in the several views, and wherein:

Figure 1 is a side elevation of the machine.

25 Figure 2 is a top plan view.

Figure 3 is a longitudinal sectional view.

Figure 4 is an end elevation.

Figure 5 is a fragmentary vertical sectional view through the hopper and its associated parts.

The machine forming the subject matter of the present invention comprises a base 10, and rising from this base are spaced bearings 11 and 12 respectively, the latter 35 being arranged in alinement, and accommodating the cracking bars or elements, which are susceptible of movement toward and away from each other for the purpose above mentioned. One of these cracking bars include 40 two sections indicated at 13 and 13', the sections being arranged in end to end relation and both sliding through the bearing 11. The other bar is indicated at 14 and slides through the bearing 12. The 45 section 13 of the first mentioned bar forcibly projects the section 13' into active relation with the bar 14 during each operation of the machine, and the section 13' is returned to normal position after each operation by 50 means of springs 13''. The section 13' is

also provided with a stop pin 13' which cooperates with the bearing 11 to limit the movement of the section 13 in one direction. The adjacent extremities of these bars are properly shaped to accommodate a nut, when the bars are moved toward each other, in active relation, and the manner in which these bars are moved toward and away from each other will be hereinafter described.

Rising from the base 10 at a suitable point 55 between the bearings above mentioned are spaced parallel standards 15, journaled between which is a transversely disposed shaft 16.

This shaft supports a tray 17 in which the nuts are singly received and cracked, and this tray 17 receives the adjacent extremities of the cracking bars 13 and 14 respectively. The tray is normally maintained in a horizontal position for the purpose just mentioned by means of coiled 60 spring 18, the latter having one end secured to the adjacent standard 15, and its other end connected to a pin projecting from the shaft 16. Supported by the bearing 12 are

65 suitable brackets 19 which are designed to support a platform, and this platform is provided with a nut receiving opening 21 which is disposed immediately above the tray 17. Resting upon the platform 20 is a hopper 22 which is adapted to contain the nuts to be cracked and the nuts from the hopper are singly conveyed to the opening 21 in a manner to be presently described. A slide valve 23 is utilized for this purpose, and operates upon the platform 20 through the hopper 22, and the valve is provided with an opening 24, which conveys a nut from the hopper to a position directly above the opening 21 in the platform, thus allowing 70 the nut to gravitate through said openings into the tray 17. The valve 23 is secured at one end to a bolt 25 which rises from the cracking bar 13, and subsequently, the valve 23 moves simultaneously with the bar 13.

75 Also supported upon the base 10 is a bearing 26 in which is journaled the main operating shaft 27, and while this shaft may be rotated by motor or by any other suitable manner, I preferably employ a large hand 80

85 90 95 100

Also supported upon the base 10 is a bearing 26 in which is journaled the main operating shaft 27, and while this shaft may be rotated by motor or by any other suitable manner, I preferably employ a large hand

wheel 28 for this purpose. The shaft 27 supports what I term a four-point cam 29, and eccentrically connected with this cam is a connecting rod 30, which is associated with the cracking bar 13 to reciprocate the latter. Fixed upon the shaft 27 is a cam 31, and this cam is disposed to engage a vertically disposed lever 32 pivoted upon the base 10 and move said lever from one direction. Connected with this lever and arranged horizontally above the base 10 is a telescopic rod, the section 33 of which is associated with the lever 32, and receives the section 34. This section has its free end connected with an arm 35 which is horizontally disposed and pivoted at a point between its ends upon a standard 36 rising from the base 10 at a point adjacent the bearing 12. The arm 35 is of a length to pass beyond the adjacent end of the cracking bar 14, and is utilized to move this bar in the direction of the bar 13 for the purposes above mentioned. A pin 37 projects from the section 34 of the telescopic rod and interposed between this pin and the adjacent end of the section 33 is a coiled spring 38 which functions in the capacity of a cushioning element. From the construction thus far described, it is obvious, that when the shaft 27 is rotated, the cracking bar 13 is moved in the direction of its cooperating bar 14, and through the tray 17.

Incident to the rotation of the shaft 27, the cam 31 contacts the lever 32 and moves the telescopic rod longitudinally of the base 10, thereby imparting rocking movement to the arm 35, which engages the adjacent end of the cracking bar 14, moving the latter in the direction of the bar 13. It is of course understood, that the valve 23 is simultaneously operated under these conditions, and as above stated, functions to singly deliver the nuts from the hopper to the tray 17. The valve conveys a nut to the tray 17 incident to the movement of the cracking bars 13 and 14 respectively away from each other, and when these bars are moving toward each other, the valve is moved through the hopper to receive another nut. The cracking bar 14 has associated therewith a spring which returns the bar to its normal position subsequent to the cracking of the nut and also after this bar has been released from a pivoted pawl 40 which holds the bar 14 stationary while the nut is being cracked. For this purpose, the cracking bar 14 is provided with teeth 41, which are engaged by a pawl 40, the latter being pivoted as at 42 upon the adjacent bearing 12, and held in effective engagement with the bar 14 through the instrumentality of a leaf spring 43. It might here be stated that after the nut has been cracked within the tray 17, and the cracking bars 13 and 14 moved away from each other, that the tray is tilted to

deposit this cracked nut into a suitable receptacle adapted to be arranged upon the base 10, and the manner in which this tray 10 is tilted will be hereinafter described. However, it is to be noted that the means for tilting the tray in a manner just described, is also utilized to affect a release of the bar 14 from the pivoted pawl 40.

For this purpose, I employ a vertically disposed lever 44 which is fulcrumed upon the bearing 12 and this lever is disposed directly in advance of the pivoted pawl 40. A link 45 is terminally connected with the upper end of this lever 44 and also with the rocking shaft 16, which is journaled between the standards 15. It is the rocking of this shaft 16 that results in the tilting of the tray 17 for the purpose mentioned, and it is manifest that when the shaft is rocked in one direction, the lever 44 is moved against the pawl 40, thereby releasing the cracking bar 14 and allowing the latter to be returned to normal position under the influence of its spring 39. Projecting from the rocking shaft 16 is an extension 46 which is arranged immediately above a bar 47 which is disposed above the base in parallelism therewith, and which bar is fulcrumed at an appropriate point in its length, and a suitable bracket 48 which rises from the base 10. The opposite end of this bar 47 is bifurcated to accommodate a roller 49, and the roller is disposed beneath the shaft 27 to be engaged by a cam 50 supported by the shaft. It is to be observed that the cam 50 is arranged so that after the cam 31 has performed its function in moving the cracking bar 14 in the direction of the bar 13, the cam 50 is brought into use, contacting the roller 49 to tilt the bar 47, moving the free end thereof in an upward direction. When the bar 47 is tilted in this manner, it engages the extension 46, and thereby rocks the shaft 16, which simultaneously tilts the tray 17 to distribute its contents, and also release the cracking bar 14 from the pivoted pawl 40. As the cam 50 is moved away from the roller 49, the spring 18 rocks the shaft in a reverse direction, thereby returning the tray 17 to normal position. The extension 46 remains in contact with the adjacent end of the bar 47 and thereby depresses this bar under the circumstances moving the bar 47 to its normal position.

Arranged at one end of the base 10 is a curved arm 51, which is bifurcated as at 52, and pivoted between the separated portions defined by said bifurcation is a lever 53. Connecting the upper end of this lever with an agitating member 54 is a link 55, so that when the lever 53 is actuated, the agitating member is reciprocated through the hopper 22 above the sliding valve 23. The lower end of the lever 53 is curved and supports a roller 56, the latter being dis-

posed to be engaged by the four-point cam 29 in a manner to oscillate this lever for the purpose mentioned. A spring 57 has one end connected to the arm 51, and its other end connected to the lever 53 adjacent the upper end thereof. Manifestly, the agitating member is reciprocated faster than the slide valve 23, inasmuch as the purpose of this member is to properly arrange the nuts 10 within the hopper, so that they can be singly conveyed to the tray 17 as described. The agitating member is semi-cylindrical in cross section, and is provided with a longitudinal slot 58, while the sides of the member also are roughened as at 59, so that the said member will operate efficiently. Manifestly, I have devised a machine of the class in question, which is not only simple in construction, but also very efficient in operation, and 20 by means of which large quantities of nuts can be cracked in quick order, the nuts being singly conveyed to the tray in which they are cracked, and subsequently disposed into a suitable receptacle 60 supported on the 25 base of the machine.

While it is believed that from the foregoing description, the nature and advantages of the invention will be readily apparent, I desire to have it understood that I do not limit myself to what is herein shown and described, and that such changes may be resorted to when desired as fall within the scope of what is claimed.

What I claim is:—

35 1. A nut cracking machine including a tray, nut cracking bars capable of movement toward and away from each other through said tray, means for conveying nuts singly to the tray, means for operating said bars, means for holding one of said bars immovable in its active position, said tray being mounted for tilting movement, and means for tilting the tray as and simultaneously effect a release of said bar.

45 2. A nut cracking machine including a tray, a hopper, means for singly conveying the nuts from the hopper to the tray, nut cracking bars capable of movement toward and away from each other through said tray, means for operating said bars, means for holding one of said bars immovable in its active position, said tray being mounted for tilting movement, yieldable means normally holding the tray in horizontal position, and 55 means for tilting said tray and simultaneously effect a release of said bar.

3. A nut cracking machine including a tray, a hopper, means for singly conveying the nuts from the hopper to the tray, nut cracking bars capable of movement toward and away from each other through the tray, means for holding one of said bars stationary in an active position, means for operating said bars, said tray being mounted for tilting movement, means for tilting said

tray, and means actuated from the last mentioned means to release said stationary bar incident to the tilting of said tray.

4. A nut cracking machine including a tray, a hopper, a slide valve operating through the hopper and singly conveying the nuts therefrom to said tray, nut cracking bars capable of movement toward and away from each other, through said tray, means for operating said bars, an agitating element slideable through said hopper, means for operating said member simultaneously with the operation of said bars, means for holding one of said bars stationary in active position, said tray being mounted for tilting movement, means for tilting said tray, and means actuated by the last mentioned means for releasing said stationary bar, incident to the tilting of said tray.

5. A nut cracking machine comprising a tray, a hopper, means for singly conveying the nuts from the hopper to said tray, means for operating said bars, said means including a rotatable shaft, a cam fixed on said shaft, a connection between one of said bars and said shaft and mechanism operated by said cam for controlling the movements with the other bar, means for holding the latter mentioned bar stationary in an active position, said tray being mounted for tilting movement, means for tilting said tray at predetermined intervals, and means actuated by the last mentioned means for releasing said bar incident to the tilting of said tray.

6. A nut cracking machine including a tray, a rock shaft supporting the tray for tilting movement, a hopper, means for singly conveying the nuts from the hopper to said tray, nut cracking bar capable of movement toward and away from each other through said tray, yieldable means for normally holding the tray in a horizontal position, means for operating said bars, means for holding one of said bars stationary in an active position, means for rocking said shaft to tilt said tray at predetermined intervals, and means actuated by said shaft for releasing said bar incident to the tilting of the tray.

7. A nut cracking machine comprising a tray mounted for tilting movement, means for normally holding the tray in a horizontal position, a hopper, means for singly conveying nuts from the hopper to said tray, a shaft mounted for rotation, means actuated from said shaft for moving said bars toward and away from each other, means for rotating said shaft, means for holding one of said bars stationary in active position, means operated from said shaft for tilting said tray, and means actuated by the last mentioned means for releasing said bar incident to the tilting of said tray.

8. A nut cracking machine comprising a tray mounted for tilting movement, means for normally holding said tray in a hori-

zontal position, a hopper, means for singly conveying the nuts from the hopper to the tray, nut cracking bars movable toward and away from each other through said tray, a shaft mounted for rotation, means for rotating said shaft, means for operating said bars and including a cam carried by said shaft, means for tilting said tray at predetermined intervals, and including a second cam carried by said shaft, means actuated by the last mentioned means for releasing said stationary bar incident to the tilting of said tray, and said cams being disposed whereby said tray is tilted just prior to the movement of the bars away from each other.

9. A nut cracking machine comprising a tray mounted for tilting movement, means for normally holding the tray in a horizontal position, a hopper, nut cracking bars movable toward and away from each other through the tray, means for operating said bars, a slide valve operating through said hopper to singly convey the nuts therefrom to the tray, means connecting the valve of one of said bars for movement therewith, means for holding the other bar stationary in an active position, an agitating member slidable through the hopper and operating above the valve, means for reciprocating said agitating member, incident to the operation of the machine, means for tilting said tray at predetermined intervals, and means actuated by the last mentioned means for releasing said stationary bar incident to the tilting of said tray.

10. A nut cracking machine comprising a tray mounted for tilting movement, means for normally holding the tray in a horizontal position, a hopper, means for singly conveying nuts from the hopper to said tray, nut cracking bars capable of movement toward and away from each other through said tray, means for holding one of said bars stationary in an active position, a shaft mounted for rotation, means for rotating said shaft, means for operating said bars and including a cam fixed on said shaft, means for tilting said platform at predetermined intervals and including a cam mounted on said shaft, means actuated by the last mentioned means for releasing said stationary bar incident to the tilting of said platform, an agitating member arranged to reciprocate through the hopper and means including a cam fixed on said shaft and having a plurality of active surfaces for operating said agitating member.

11. A nut cracking machine comprising a tray mounted for tilting movement, means for normally holding the tray horizontally, a hopper, nut cracking bars movable toward and away from each other through said tray, a slide valve operating through the hopper to singly convey the nuts therefrom to said

tray, said valve having connection with one of said bars for movement therewith, a shaft mounted for rotation, a connection between the shaft and one of said bars for operating the latter, a cross arm mounted for pivotal movement and arranged to engage the other of said bars to move the latter to an active position, yieldable means for returning the latter mentioned bar to normal position, a cam fixed on said shaft, a reciprocatory rod actuated by said cam and connected with said arm to operate the latter, a cushioning member arranged in the length of said rod, means for holding one of said bars stationary in an active position, means operated from said shaft for tilting the platform at predetermined intervals, and means actuated by the last mentioned means for releasing said bar incident to the tilting of said platform.

In testimony whereof I affix my signature.
